UNITED STATES PATENT OFFICE.

JOHN P. ADAMS AND GEORGE I. LEONARD, OF CHICAGO, ILLINOIS.

WINDOW-VENTILATOR.

1,241,185.

Specification of Letters Patent. Patented Sept. 25, 1917.

Application filed February 2, 1917. Serial No. 146,101.

To all whom it may concern:

Be it known that we, JOHN P. ADAMS and GEORGE I. LEONARD, citizens of the United States, residing at Chicago, in the county of 5 Cook and State of Illinois, have invented a new and useful Improvement in Window-Ventilators, of which the following is a specification.

Our invention relates, more particularly, 10 to the type of window ventilators which are formed of a frame work adapted to fit within the confines of a window sash and between the sill and a partially raised window, with a covering of interstitial material 15 of such character that air may more or less freely pass therethrough.

Our primary object is to provide improvements in ventilators of the type, and for the purpose, above referred to, to the end that 20 they may be made at relatively slight cost, be simple of construction, readily applied to and removed from, operative position, and permit, when desired, the ready renewal and replacing of the interstitial material; 25 another object being to provide a desirable form of ventilator which may use fabric as a screening material and permit of the ready renewal and replacement thereof.

Referring to the accompanying drawings: 30

Figure 1 is a view in front elevation of a ventilator constructed in accordance with our invention.

Fig. 2 is a plan view of the construction 35 shown in Fig. 1.

Fig. 3 is a broken enlarged view taken at the line 3 on Fig. 1 and viewed in the direction of the arrow.

Fig. 4 is a broken view of one of the 40 corners of the frame of Fig. 1, showing portions of the metal casing or covering broken away.

Fig. 5 is a broken view in end elevation of the frame.

Fig. 6 is an enlarged broken section taken 45 at the line 6 on Fig. 2 and viewed in the direction of the arrow.

Fig. 7 is a section taken at the line 7 on Fig. 1 and viewed in the direction of the 50 arrow; and

Fig. 8, a plan view of the screening material for the structure shown in Fig. 1.

According to the preferred illustrated embodiment of our invention, the frame of the 55 ventilator is formed of two telescoping sections 9 and 10, which are formed of end

pieces 11 and 12 respectively, and members 13 and 14 and 15 and 16 respectively, each of the sections 9 and 10 being thus of U-shape as illustrated. The frame members 60 9 and 10 are each preferably formed primarily of hollow metal members 17 of a cross-sectional shape as shown more particularly in Figs. 4 and 7. These members contain along their outer sides continuous slots 65 as represented at 18 whereby the outer edges of the frame are slotted throughout their extent, thus providing a slot which extends continuously around the frame. While the cross-sectional form of the metal members 70 17, forming parts of the members 13 and 14, as the same as the members 17 forming parts of the members 15 and 16, they are of slightly less cross-sectional dimensions whereby the members 13 and 14 telescope 75 with the members 15 and 16 as represented, this feature of the construction, as will be more fully explained, permitting the frame work to be expanded or contracted to adapt it to be positioned in place and removed 80 therefrom as desired.

The metal members 17 forming parts of the frame members 11, 12, 13, 14, 15, and 16 are all filled with strips 19, preferably of wood which are grooved as indicated at 20 85 to register with the slots 18 in the members 17, the strips 19 reaching short of the free ends *i.e.* the left hand ends in Fig. 1, of the frame members 10 and 16, as illustrated in Figs. 3 and 6. The casing 17 forming the 90 various frame members as stated and the filler blocks 19 may be secured together in any suitable way. In the particular construction illustrated the front and rear walls of the members 17 adjacent the upper and 95 lower ends of the frame members 11 and 12 extend continuously to the extreme outer ends of the frame as represented at 21 of the front wall of the member 17 adjacent the lower end of the member 12, the upper and 100 lower ends of the members 17 forming parts of the frame ends 11 and 12, being mitered, as indicated at 22, and over-lapping portions 21 as shown. The upper and lower extremities of the rear sides of those of the members 17 which in part form the frame members 11 and 12 are extended to the upper and lower edges of the ventilator frame to 105 overlie the extended portions of the rear faces of the members 17 forming the frame members 13, 14, 15 and 16. Any suitable fastening means, as for example nails as

represented at 23, may be driven through the members 17 and filler blocks 19 and through the over-lapped parts of the members 17 at the rear side of the frame. If desired cross-pieces 24 secured to the members 13 and 14 and 15 and 16 respectively of the frame, may be provided for bracing the frame sections.

It will be understood from the foregoing 10 that the frame thus provided contains a groove which runs continuously around its outer surface and that the frame may be, within certain limits, contracted to reduce its length and expanded to increase its length 15 by sliding the telescoping parts one on the other, and without impairing the continuity of the groove hereinbefore referred to.

Any suitable interstitial material for 20 forming the screening element of the ventilator, to permit air to pass therethrough, but preferably to intercept soot and the like, may be employed it being desirable, however, that the material used be comparatively finely woven duck which, by preference, is provided of the shape shown in Fig. 8 and of such dimensions that the portion 25 of the piece of fabric bounded by the lines 25, 26, 27 and 28 in Fig. 8 shall be substantially the same as the outside dimensions 30 of the frame when it is in extended position. The screening material of Fig. 8, represented at 29, is, in accordance with our invention, laid across the rear side of the frame and the flaps 30, 31, 32 and 33 provided 35 about the four sides of the material 29, are folded forwardly to overlie the four grooved sides of the frame. The material 29 is then fastened in place to cause it to extend tautly across the rear side of the 40 frame, by means of cleats represented at 34, and which may be of wood or any other suitable material. These cleats are somewhat narrower than the slots 18 and the grooves 20 and are adapted to hold the 45 material 29 in place by inserting them into the grooves with the flaps 31 to 33 inclusive interposed between the cleats and the grooves. The dimensions of the cleats however are such that when positioned in the 50 grooves as stated with the material 29 interposed between them and the grooves, they will extend a slight distance beyond the marginal edges of the frame for a purpose hereinafter set forth. The cleats do not 55 completely fill the upper and lower grooves from end to end of the frame, the cleats for these parts of the frame being each formed of two sections, in other words, two sections of cleat for the upper groove and two sections 60 for the lower, the combined length of the cleats for the upper groove being less than the length of the frame, and the same being the case with the lower cleats, whereby a space, preferably about three-quarters 65 of an inch long, is provided between the

adjacent inner ends of the cleat sections at both the upper and lower grooves, as represented at 35 on Fig. 6. In other words, when the frame is partly extended the filler blocks 19 for both the upper and lower 70 portions of the frame reach short of each other and likewise the cleat sections co-operating with the grooves in these parts.

To use the construction in the preferred manner, the width of the space into which the ventilator is to be fitted is measured and the frame sections 9 and 10 adjusted one upon the other at their telescoping connection, to make the frame of the length of said space. The material 29, cut to the form 75 and dimensions as hereinbefore stated, is then applied to the rear face of the frame and secured at its flaps in the continuous groove about the frame by means of the cleats, to extend tautly across the frame. 80 Inasmuch as the ventilator is to fit into the grooves in which the window travels, it is necessary that the frame be contracted to so position it for use, and this is readily accomplished by the operator further telescoping 85 the frame sections 9 and 10 with each other sufficiently to permit of the insertion of the frame to place. Inasmuch as the cleats when the frame is extended to a size to fit the window opening, reach short of each 90 other, and likewise the fillers 19 at the top and bottom of the frame reach short of each other, the frame may be readily contracted for the purpose stated, the screening material 29 buckling or gathering at the portions 95 of the frame adjacent the points at which the frame members telescope, the screening material however straightening out to taut condition upon the introduction of the ventilator into the window opening and the expanding of same into place.

It is desired that some means be provided for releasably holding the frame sections 9 and 10 in expanded condition to avoid 100 danger of the frame falling to the pavement below. Desirable means for this purpose are shown in the drawings, these means comprising a spring finger 36 riveted at one end, as indicated at 37, to the front face of the members 17 forming a part of the frame member 15 and carrying a dog 38 which works through an opening 39 in the member last referred to and is adapted to enter, and engage the wall, of any one of the notches provided in the member 13. The dog 105 38 is so formed that it presents an abrupt shoulder to the wall of the opening 40 into which it extends, being beveled or rounded at its opposite side, as represented at 41, so that it will automatically slide over the edges of the opening in the act of expanding the frame to position it for use.

In the use of the device in a window opening, the sides of the window opening by 110 engaging the cleats at the ends of the frame 115

serve to prevent accidental withdrawal of the cleats from the grooves and the engagement of the sill and the bottom of the window, with the cleats along the lower edge of 5 the frame and the upper edge thereof serves to hold these cleats in position. In this connection it may be said that while the metal casing 17 of the outermost telescoping part of the members 10 and 16 extends upwardly 10 and downwardly respectively at least the thickness of the metal, beyond the corresponding surface of the members 13 and 14 respectively, the upper surfaces of the cleats in the upper groove of the frame extend in 15 the same horizontal plane as the grooves 20 in the filler blocks and are made of such depth that their innermost walls are in alinement, and this same condition is true of the groove and cleat construction at the bottom of the frame. Thus by our invention 20 the feature of telescoping the frame members is provided without presenting objectionable jogs, which if they exist would impair the joints between the frame and the 25 sill and the frame and the bottom of the window.

While we have illustrated and described the particular construction in which our invention is embodied, we do not wish to be 30 understood as intending to limit it thereto, as the same may be variously modified and altered without departing from the spirit of our invention, it being our intention to claim our invention as broadly as the prior 35 state of the art will permit.

What we claim as new and desire to secure by Letters Patent is:

1. A ventilator comprising a frame 40 formed of telescoping sections arranged in alinement, and a strip of screening material secured to said frame to extend over a face thereof across said sections, said sections being relatively adjustable with said strip in place.

45 2. A ventilator comprising a frame formed of telescoping sections and containing grooves in its outer edges, a strip of screening material extending over a face of said frame across said sections, and means 50 securing said screening material at its edges in said grooves, said sections being relatively adjustable with said strip in place.

55 3. A ventilator comprising a frame formed of telescoping sections and containing grooves in its outer edges, a strip of screening material extending over a face of said frame across said sections, and cleats 60 clamping said screening material at its edges in said grooves, said sections being relatively adjustable with said strip in place.

65 4. A ventilator comprising a frame formed of sections adapted to be adjusted toward and away from each other, a strip of relatively flexible screening material extending over a face of said frame across said sec-

tions, and means for securing said material to said frame constructed and arranged to permit said frame-sections to be adjusted without disturbing the connection of said screening material with said frame. 70

5. A ventilator comprising a frame formed of sections having hollow metal members, with the frame-members of said sections telescoping with each other, and a strip of screening material secured to said 75 frame to extend over a face thereof across said sections, said sections being relatively adjustable with said strip in place.

6. A ventilator comprising a frame 80 formed of sections having hollow metal members, with the frame-members of said sections telescoping with each other and containing grooves in their outer edges, a strip of screening material extending over a face of said frame across said sections, and means 85 of extending into said grooves and securing the said material therein at the edges of the latter, said sections being relatively adjustable with said strip in place.

7. A ventilator comprising a frame 90 formed of sections having hollow metal members, with the frame-members of said sections telescoping with each other and containing grooves in their outer edges, filler strips in said frame members, grooved to 95 register with the grooves in the latter, a strip of screening material extending over a face of said frame across said sections, and means extending into said grooves and securing the said material therein at the edges 100 of the latter, said sections being relatively adjustable with said strip in place.

8. A ventilator comprising a frame 105 formed of telescoping sections and containing grooves in its outer edges, the bases of said grooves in the top and bottom of said frame alining respectively, screening material extending over a face of said frame, and cleats in said grooves securing said 110 material at its edges to said frame, the outer sides of said cleats at the top and bottom of said frame alining with each other, respectively.

9. A ventilator comprising a frame 115 formed of telescoping sections and containing grooves in its outer edges, the bases of said grooves in the top and bottom of said frame alining respectively, screening material extending over a face of said frame, and cleats in said grooves securing said 120 material at its edges to said frame, the upper surfaces of said cleats at the top of said frame alining with each other and the lower surfaces of said cleats at the bottom of said frame alining with each other, said upper 125 and lower surfaces being located above the upper and lower edges respectively, of said frame.

10. A ventilator comprising a frame 130 formed of adjustable sections, screening

- material secured to said frame and extending over a face thereof, and releasable means for holding said sections in extended position operating automatically to permit said sections to be adjusted away from each other.
11. A ventilator comprising a frame formed of adjustable sections, screening material secured to said frame and extending over a face thereof, a spring member secured to one frame-section and carrying a projection, and means on the other of said frame-sections for engagement with said projection to prevent said sections from contracting until said spring member is flexed
- 10 to withdraw said projection from said means, said projection being so shaped as to permit said frame to be extended without manually flexing said spring member.
12. A window ventilator formed of a frame work provided in two sections telescoping with each other at their ends, said sections being formed of hollow sheet metal members and a filler of wood partially filling the said members, said sections containing
- 15 a groove extending along the outer edge
- 20
- 25

of the ventilator, screening material extending over the entire area of one side of the ventilator, clamping means engaging said screening material and extending into said groove for holding the screening material in stretched condition over the frame work, and a ratchet spring catch co-operating with both of said sections and adapted to permit said sections to be spread apart to fit the ventilator to the window opening and automatically clamp said sections in extended position.

13. A ventilator having hollow metal sections open along one side and presenting slots, filler strips partially filling the interior of said metal sections and containing grooves registering with said slots, screening material for said sections, and cleats engaging said screening material and extending through said slots and into said grooves for holding the screening material in position.

JOHN P. ADAMS.
